UNITED STATES PATENT OFFICE.

WILLIAM G. HARTWIG, OF CHICAGO, ILLINOIS.

ELECTRIC HEATER SYSTEM.

Application filed April 9, 1923, Serial No. 630,731. Renewed February 25, 1927.

My invention relates to thermostatically controlled electric heater systems such as are commonly installed in trolley cars and the like, and has for its object the protection of 5 the system in case of the accidental grounding of any of the heaters.

The invention may best be understood from the following description of a preferred installation. It is to be understood, however, 10 that the specific disclosure is for the purpose of exemplification only and that the scope of the invention is defined in the following claims, it being my intention to secure thereby whatever invention is disclosed, in its 15 broadest scope.

In the drawings accompanying and forming a part of this specification Fig. 1 is a diagrammatic view showing a complete heater system embodying my invention in its preferred form; Fig. 2 is a vertical section of the automatic cutout thereof on a plane parallel to the supporting panel, and Fig. 3 a vertical section at right angles to the plane of Fig. 2 on the line 3—3 thereof.

Referring first to the diagram shown in Fig. 1, it will be observed that the electric heaters 4 are arranged in two circuits, there being six heaters in each circuit in this particular instance, the respective circuits being 20 fused at 5 and jointly connected by wire 6 to the movable member 7 of the contactor. The stationary member 8 of the contactor is connected to line as shown. The movable member 7 is controlled by an electro-magnet 9, shown diagrammatically, which, when the temperature in the car or other compartment heated by the system is below the desired temperature for which the thermostat of the system is set, is energized from the line 25 through a circuit comprising wire 10, resistor 11, wire 12, winding 13, wire 14, fuse 15 and ground 16. A thermostat 17 is connected in shunt to the operating coil of the contactor and adapted to short-circuit the latter when the temperature of the compartment in which the system is located rises to the maximum for 30 which it is designed. A condenser 18 connected across the terminals of the thermostat reduces sparking on the opening of the thermostat switch. A hand-switch 19 may also be utilized when desired to short-circuit the coil of the contactor.

The automatic cut-out, to which the invention more particularly relates, is indicated at 20 in the diagram but will be more specifically

described in connection with Figs. 2 and 3. The movable and stationary contacts 21, 22 of the cut-out are connected across the terminals of the contactor coil as best seen in Fig. 1. The stationary contact is carried by a bracket 23 mounted on the panel and the movable contact is carried by an arm 24 hinged to a bracket 25 mounted on the panel as seen in Figs. 2 and 3. The arm is gravity-operated and when it is not sustained by the device to be presently described drops to close the shunt circuit, whereby the contactor is caused to open the heating circuit.

The device for normally holding the automatic cut-out switch open and which constitutes the present invention comprises an inverted T-shaped latch 26 which is pivotally and bodily movable upon the panel and the central limb of which normally supports the arm 24 in a position in which the automatic cutout is open. It is mounted upon an angle-iron or bracket 27 by means of a screw-pin 28 on such bracket which extends through a slot 29 in the latch. The angle-iron 27 is supported by a sheet-metal bracket 28 attached to the panel. An insulating block 30 is secured to the under-face of the arm 24 and normally rests upon the upper end of the latch. When the latch is tilted to either side of the central position, as in case of the grounding of any of the heaters, it permits the arm to drop to close the switch. The latch extends through an opening 31 in bracket 28 of proper dimensions to permit but limit the swing of the latch in either direction from the central position shown. The lateral arms of the latch are notched at 32.

A pair of solenoids 33—33 are suspended from the bracket 28 on opposite sides respectively of the latch and their cores are provided on their lower ends with discs 34—34 which engage the notches in the lateral arms of the latch respectively. The coils 35—35 of the solenoid are connected in the respective parallel circuits of the heaters, one terminal of each coil being connected to the terminal of the last heater in its respective circuit. The other terminals of the coils of the solenoids are connected together at 36 and to an ammeter or other current indicating device at 37, the other terminal of which is connected by wire 38 to ground at 39.

When the current is off and the contactor open the latch is in its central lowered posi-

tion as shown in the drawing, and when the contactor is closed and the heater circuit intact, the latch remains in the intermediate position but is raised by the cores of the solenoids to its upper position.

In the event of a ground in either of the heater circuits, one of the solenoid coils will be de-energized but not the other, and hence its core will drop tilting the latch and permitting the cut-out switch to close and short-circuit the contactor coil, thus opening the heater circuits. Thus during normal operation, the latch will merely reciprocate in a vertical direction slightly raising and lowering the movable member of the cut-out switch but without permitting it to close. But in the event of a ground while the heating current is on, it immediately tilts permitting the contactor to be opened.

For convenience in restoring the arm of the switch to normal position, and permitting the latch to resume its intermediate position, the arm 24 is provided with a pivoted finger piece 40 which extends through a hole 41 in a brace 42 connected between the upper end of bracket 28 and the outer end thereof.

The indicator 37, which is exposed for observation will show a ground in the heater circuits. Obviously the condition of the circuit could be indicated by noting the position of the latch or the latter might carry or operate an indicator or signal in some exposed position.

I claim:

1. In a thermostatically constructed heater system for electric cars and the like, a plurality of heaters arranged in two parallel circuits, an electro-magnetically controlled contactor controlling the supply of current to said heaters, a thermostat normally controlling the circuit of said contactor, a normally open switch adapted to short circuit the thermostat when closed, means normally holding the switch open, said means jointly controlled by the respective parallel heater circuits, whereby a short-circuit in either circuit will permit said switch to close.

2. In a thermostatically constructed heater system for electric cars and the like, a plurality of heaters arranged in two parallel heating circuits, an electro-magnetically controlled contactor controlling the supply of current to said heaters, a thermostat normally controlling the circuit of said contactor, a normally open switch adapted to short-circuit the thermostat when closed, a latch normally holding the switch open, electro-magnetic coils in the respective parallel heating circuits holding said latch in an intermediate position when both said circuits are energized but permitting it to move from said position and release the switch when either of said circuits is de-energized.

3. In apparatus of the class described, a plurality of heaters arranged in two parallel

heating circuits, an electro-magnetically operated contactor controlling the supply of current to said heaters, a thermostat normally controlling the circuit of said contactor, a normally open switch adapted to short-circuit the thermostat when closed, electro-magnets the coils of which are arranged in the respective parallel circuits, a latch engaging said switch and pivotally movable, the armatures of said electro-magnets engaging the latch to give it a bodily movement when the coils of said electro-magnets are energized and de-energized together and to give it a tilting movement when de-energized singly.

4. In an electric heating system, parallel heating circuits, a contactor controlling the same, electromagnetic means operating the contactor, a cut-out switch controlling said operating means, a device normally holding the cut-out switch open, and coils in the respective parallel circuits jointly controlling said device.

5. In an electric heating system, parallel heating circuits, a contactor for opening and closing the same, electro-magnetically operated means operating the contactor, a cut-out switch controlling the circuit of said means, a pair of electro-magnetic means respectively in said parallel heating circuits, and a tilting device normally holding the cut-out switch open controlled jointly by the last said electro-magnetic means.

6. In a heating system, parallel heating circuits, a contactor, electro-magnetic means for operating the same, a cut-out switch controlling the circuit of said means, a tilting and bodily movable device normally maintaining said switch open, and electro-magnetic means respectively in said parallel circuits jointly giving said device a bodily movement and severally a tilting movement.

7. In a heating system, a pair of parallel heating circuits, a contactor controlling the same, electro-magnetically operated means controlling the contactor, a cut-out controlling the circuit of said electro-magnetically operated means, said cut-out comprising a pivoted arm, a latch normally supporting said arm and having a bodily movement toward and from the same, and a tilting movement releasing the arm, and electro-magnetic means in the respective parallel heating circuits jointly controlling the bodily movement of the latch and severally tilting the same.

8. In a heating system of the class described, a pair of parallel heating circuits, a contactor controlling the same, electro-magnetic means controlling the contactor, a thermostat opening and closing the circuit of said electro-magnetic means, an automatic cut-out also controlling said circuit, a latch normally maintaining said cut-out switch open, and electro-magnetic devices arranged in said parallel circuits and jointly controlling said cut-out.

9. In a heating system of the class described, a pair of parallel heating circuits, a contactor opening and closing said circuits, electro-magnetic means controlling the contactor, an automatic cut-out for said electro-magnetic means comprising a pivoted arm, a latch having a pin and slot connection to its support normally maintaining said arm in a position to open the switch, solenoids on opposite sides of the latch, the cores of which are loosely connected thereto and adapted to jointly reciprocate the latch and severally to tilt the same, the coils of said solenoids being connected to the respective parallel circuits. ¹⁰

WILLIAM G. HARTWIG.
